UNITED STATES PATENT OFFICE.

VITO GUARIGLIA, OF BROOKLYN, NEW YORK.

PEN AND PENCIL CLIP.

1,370,206.

Specification of Letters Patent.

Patented Mar. 1, 1921.

Application filed June 1, 1920. Serial No. 385,725.

To all whom it may concern:

Be it known that I, VITO GUARIGLIA, a citizen of Italy, residing at Brooklyn, in the county of Kings and State of New York, have invented certain new and useful Improvements in Pen and Pencil Clips, of which the following is a specification, reference being had to the accompanying drawings.

10 This invention relates to clips and particularly to a clip for preventing disengagement of a writing implement from a pocket or support.

An object of the invention is to provide a 15 clip of this character constructed for use in connection with pens, pencils, and like writing implements of all sizes.

Another object of the invention is to provide a clip of this character including a novel 20 clamp adapted to engage all sizes of writing implements, said clamp being adjustable to accommodate the size of implement and to firmly engage the same at all times.

A still further object is to provide a clip 25 of this character including clamping means adapted to be secured to a pencil or pen, and a clip pivoted to said means, said clip being movable away from or toward the pencil to prevent the same from disengaging the garment or support to which it is applied.

With these and other objects in view, the invention consists in the improved construction and arrangement of parts to be herein-after more particularly described, fully 35 claimed and illustrated in the accompanying drawings, in which:—

Figure 1 is a vertical elevation of the pen and pencil clip applied to a pencil,

Fig. 2 is a section taken on line 2—2 of

40 Fig. 1,

Fig. 3 is a section taken on line 3—3 of

Fig. 2, and

Fig. 4 is an enlarged side elevation.

Referring to the drawings, 5 designates a 45 clip including a finger piece on its end 6, the end 7 being formed into a jaw. Projecting from the intermediate portion of the clip 5 is a pair of ears 8 which are disposed in spaced parallel relation to each other, each 50 ear having an opening 9, the purpose of which will be herein-after described.

In order to permit the clip to be used in connection with pencils and pens of various sizes, a supporting member or plate 10 is 55 provided, said plate being preferably rec-

tangular in form and having an ear 11 extending from each end thereof, said ears being disposed in spaced parallel relation to each other. An opening 12 is provided in each ear and is adapted to register with the 60 openings 9 in the ears 8. A shaft 13 is disposed between the ears and within the registering openings 9 and 12, so as to pivotally connect the ears 11 to the ears 8. A coil spring 14 is disposed on the shaft 13 between 65 the ears, one end of the spring being connected to the adjacent portion of the clip 5 while the other end of the spring is connected to the adjacent portion of the plate 10. By this means, the clip and plate are 70 urged toward each other at all times.

A clamp 15 is provided for engagement with the writing implement and comprises a length of resilient material bent at its intermediate portion upon itself to provide folds 75 16, said folds being extended back upon themselves as at 17 and then outwardly and inwardly to provide clamps 18. The portion 17 and folds 16 are provided with registering openings 19, the opening in one of the portions 17 being threaded. An adjusting screw 20 is passed through the registering openings 19 and through the threaded opening of the portion 17 above mentioned. This screw is intended to draw the 80 clamps 18 toward each other against the resiliency of the folds 16 and portion 17. The clamp is secured to the plate 10 at the junction of the portion 17 with the folds 16.

A pen, pencil or like writing implement is 85 secured between the clamps 18, by rotating the screw 20. The pencil then forms a portion of the clamping means. When the clip is engaged with a support or garment, the spring 14 forces the clip 5 toward the pencil 90 or writing implement, thereby clamping the support or garment between the clip and the implement. As the clamps 18 are not frictionally engaged but firmly secured to the writing implement, it is impossible for the 100 implement to become accidentally disengaged from the clamps.

Another important feature of this device is that when the clip is being applied to the pocket of the garment or support it is not 105 necessary to ascertain whether or not the garment or support is properly positioned between the clip and the implement, as the clip cannot possibly avoid engagement with the pocket or support as it is moved away 110

from the implement by means of the finger piece 6. This provides ample room for the insertion of the garment or support between the clip and the implement. In addition to 5 this it may be applied to all types of writing implements regardless of their shape or size.

What is claimed is:—

- 10 1. A device of the character described comprising a jaw member, a supporting member pivoted to the jaw, a clamp carried by said supporting member, said clamp comprising a length of resilient material folded several times upon itself at its intermediate portions, the end portions of said length being formed into arcuate clamping jaws, and a screw extending through the folded por-

tions of said length for moving said jaws into engagement with a writing implement.

2. The combination with a writing implement, of an adjustable clamp embracing 20 said implement, a clip pivoted to said clamp, the end portions of said clip extending beyond the clamp, one end of said clip being formed into a jaw, the portion of said writing implement adjacent the jaw of the clip 25 coacting therewith to provide a clamp, and means for constantly urging the jaw of the clip toward the writing implement.

In testimony whereof I hereunto affix my signature.

VITO GUARIGLIA.
